UNITED STATES PATENT OFFICE

2,457,096

METHOD OF HEATING FLUIDS

Harry R. Swanson, Katonah, N. Y., assignor, by
mesne assignments, to Petro-Chem Process
Company Incorporated, New York, N. Y., a cor-
poration of Delaware

Application March 20, 1943, Serial No. 479,923

2 Claims. (Cl. 196—66)

1

This invention relates to a method of heating fluids and their mixtures under controlled temperature conditions and refers more particularly to a method in which separate fluids are initially heated in separate zones and then simultaneously heated in separate streams in a third zone and thereafter being mixed, either on discharge from the third zone or prior thereto, in which latter case the mixture is heated before leaving the third zone. The control over the temperature of the liquids when mixed is accomplished by the temperature to which each of the fluids is heated in the initial zones of heating.

Where two fluids are to be heated to different temperatures in order to effect a mixture at a desired high temperature or when it is desired to mix fluids at different high temperatures and subsequently heat the mixture, it has been found difficult to maintain control over the temperatures of the respective fluids except by controlling the firing rate of the furnaces in which the fluids are heated or regulating the quantities of fluids charged to the heaters. If quantities are critical to the mixture, variations are undesirable and objectionable. Furthermore, controlling the rates of firing may give a modicum of satisfaction where temperatures are relatively low and there is no necessity for heating the fluids after mixture but at high temperatures any semblance of control over the temperatures of the individual fluids or the mixture soon disappears.

By heating the separate fluids in separate heaters fired separately, then heating both fluids in separate streams simultaneously in a third zone of heating where approximately the same amount of heat is supplied in proportion to the heating surface, control can be accurately maintained over the ultimate or final temperature of the individual fluids before mixture by the control of the outlet temperature of the individual fluids as discharged from the initial zones of heating.

As an example, in the conversion of light hydrocarbons as practiced by one of the present day methods, a light oil such as naphtha, which may be designated fluid A, is heated in a first zone to an outlet temperature of from 900 to 1000° F., a second normally gaseous fluid, such as C₄ and lighter hydrocarbons, which may be designated fluid B, is heated separately in a second zone to a temperature different than that to which the fluid is heated in the first zone. The two streams of fluids A and B are then passed in separate streams through a third zone where they are simultaneously heated by a common heat source to increase the temperature of the two

fluids correspondingly. By controlling the outlet temperature of the respective fluids A and B as discharged from the first and second zones, their discharge temperature from the third zone, where 5 the fluids are combined, can be accurately regulated. In this manner there is established definite temperatures at which the hydrocarbon fluids are mixed, thereby obtaining optimum conditions for reaction and maximum yields of desired products such as the olefins for subsequent alkylation and C₄ hydrocarbons such as butenes and butadienes essential to the synthetic rubber program. 10 Different results in the character and yields of the products may be obtained by combining the 15 streams before discharge from the third zone of heating, permitting the heating of the mixture in this final zone for a predetermined period. Also conditions may be altered including temperatures, point of mixture and other variations, 20 according to the stocks treated and the products desired.

In the accompanying drawings which form part 25 of the instant specification and are to be read in conjunction therewith, and in which like reference numerals are used to indicate like parts in the various views,

Fig. 1 is an elevational side view with parts in 30 section of an apparatus in which the method may be practiced,

Fig. 2 is a developed view of a heating cycle in 35 which two separate fluids are preheated in separate stages, superheated in a third stage and mixed upon discharge from the final stage,

Fig. 3 shows a developed view of a heating 40 cycle from which the first two preheating stages of the separate fluids have been omitted and a modified form of the final or third zone in which the separate fluids are superheated and mixed prior to discharge so that the mixture is subjected to heating in the third zone,

Fig. 4 is an elevational view partly in section 45 of a horizontal furnace construction corresponding, in so far as the heating cycle is concerned, with Figs. 1 and 2. The separate fluids are heated in separately fired zones and superheated simultaneously in a third zone receiving its heat from a common source of heating, the mixture of the fluids taking place on discharge from the final zone.

Referring to the drawings and particularly 50 describing the apparatus as shown in Fig. 1, three separate furnaces are shown having outer casings 55 which surround cylindrical combustion chamber fired by gas burners diagrammatically shown at 44. The heater casings are lined with suitable

insulation and fire brick shown diagrammatically at 12. The furnace at the left hand side of the figure for convenience is designated by the letter A, the furnace or heater at the right hand side of the figure by the letter B and the central furnace by the letter C. Around the interior of each of the furnaces are arranged a plurality of vertical heat exchange tubes 13 which are connected at the top and bottom by means of return bends and suitable clean-out plugs conveniently arranged to permit cleaning of the separate banks of tubes and removal of the tubes in case repairs are necessary. In so far as the general construction of the heaters is concerned, they are generally identical to the construction described in Patent No. 2,276,527, issued March 17, 1942.

Suspended from the upper part of the combustion chamber in each of the heaters A, B and C by means of rods or supporting hangers 14 are conical baffles or deflection cones 15 which serve to divert the combustion gases in the upper part of the combustion chambers outwardly, thereby increasing the efficiency of the heaters by restricting the combustion gas passageway and concentrating the convection heat upon the upper portion of the tubes. To obtain the maximum advantage of this convection heat in the convection zone, extended surface in the form of longitudinal fins 16 are attached to the surfaces of the tubes in this section. Due to the temperatures involved, the extended surfaces or fins 16 are used only on the furnaces A and B. Due to the high inlet temperature of furnace C, the fins would be relatively ineffective in removing heat from the exit flue gas. This heat may be conserved, however, by installing an air pre-heater above the furnace in the path of the flue gases which preheats the air supplied to the burners. Furthermore, by preheating the air to the burners in this manner, the flame burst temperature is increased, which may be desirable for certain types of operations. The furnaces are supported by standards 17 and are surmounted by a short tapered breeching 18 and chimneys or stacks 19. In each of the heaters the passage of the combustion gases is substantially the same. From the burners the gases rise, heating the surfaces of the tubes arranged around the inside of the combustion chambers. Near the upper part of the heaters the gases are diverted outwardly by the deflection cones. In heaters A and B the gases pass through the annular space between the cylindrical portion of the baffles where the extended surface fin tube sections of the heating tubes are located. After passing the baffles the combustion gases pass through the upper part of the furnace through the tapered breechings 18 to stacks 19.

Describing now the manner in which the fluids are heated in the apparatus shown in Fig. 1, a first fluid is supplied to heater A through pipe 20 and is passed through the tubes of the heater from the inlet 20 to the discharge 21. From discharge pipe 21 the fluid passes through transfer pipe 22 to inlet pipe 23 of heater C. In a similar manner fluid is charged to heater B through pipe 25 and after passing through the heating tubes (not shown), is discharged through pipe 26, transfer line 27 and thence to inlet pipe 28 of heater C.

The vertical tubes in heater C may be divided into a plurality of banks but for simplicity here heater C in Fig. 1 is divided into two banks of tubes, a single bank covering one-half of the combustion chamber for each fluid. The fluid

from A is heated in one of these banks and the fluid from heater B in the other bank. After heating in furnace C the A fluid is discharged through outlet 24 and the B fluid through outlet 29. The two fluids are then combined at a T or manifold connection 30 and the mixture removed through pipe 31. This mixture passes off through pipe 31 where it may be cooled, quenched or otherwise treated.

10 Describing now the developed view shown in Fig. 2, the tube section for heating the first fluid is designated by the letter A and the tubes by numeral 13. The tube bank for heating the second fluid is designated by the letter B and the tubes by the numeral 13a. The third heater, which superheats the two fluids, is designated by the letter C, the tube banks therein designated by the numerals 13b, 13c, 13d and 13e. In this figure, in place of passing the separate fluids in single banks of tubes through heater C, the fluid from heater A is divided and flows through a plurality of separate banks designated by numerals 13b and 13c. The fluid from heater B, instead of flowing through a single bank of tubes as described and shown in Fig. 1, is in this figure passed through heater C in a plurality of banks of tubes, namely, tubes designated by the numerals 13d and 13e. In other words, the first fluid is charged to the tubes in heater A through pipe 20 and after passing through tubes 13 is discharged through pipe 21, after which it passes through transfer pipe 22 and is introduced to banks of heating tubes 13b and 13c through inlet manifold 23. A second fluid charged to heater B is introduced through pipe 25 and after passing through tubes 13a is discharged through line 26 and passes through transfer pipe 27 to be introduced into the banks of heating tubes 13d and 13e through inlet manifold 28. The separate fluids are combined on discharge from the heater C at T connections 30 and pass out through pipe 31 as described in Fig. 1.

Fig. 3, as suggested in the description of the figure, shows only heater C with the corresponding tube banks 13b, 13c, 13d and 13e, as shown in Fig. 2. In this figure, however, in place of combining the superheated fluids on their discharge from heater C, the fluids are combined within the heater itself at connections designated by the numerals 32 and the mixture is thereafter heated in separate tubes or bank of tubes, diagrammatically shown at 33, after which the heated mixture is discharged through pipe 34, corresponding to the discharge pipe 31 in Fig. 2. This arrangement, after effecting a union of the fluids within the heater, provides a means for heating the mixture to any desired degree subsequent to their combination.

In Fig. 4 is shown a horizontal type furnace, as distinguished from the vertical heaters shown at Fig. 1, consisting of vertical walls 35 surmounted by a top 36 built of brick and properly insulated and lined with suitable refractories. The furnace is divided into separate heating chambers A, B, and C, corresponding to the separate heaters shown in Fig. 1 by means of baffle walls 37. Combustion gases are supplied to the separate chambers by means of burners 11. The separate chambers A, B, and C are open at the top so that the combustion gases pass off to a breeching 18 and out through a chimney 19. As in Fig. 1, the first fluid is introduced through pipe 20 and is circulated through a plurality of horizontal tubes 13 arranged around the interior of combustion chamber A. A second fluid is introduced

through pipe 25 and is passed through tubes 13a horizontally positioned upon the walls of combustion chamber B. The first fluid passes through transfer pipe 22 and flows through chamber C through horizontal tubes 13b while the second fluid passes over baffle wall 37 through transfer line 27 and is circulated through tubes 13d in chamber C. The two separate fluids, after receiving heat from a common source 11 in chamber C, are combined at T connection 30 and flow out through pipe 31. Although we have shown tubes 13b and 13c equal in number and size to tubes 13d and 13e, it may be desirable to vary the number of tubes in each bank with respect to each other to obtain the desired heat distribution and desired resultant temperatures.

In Fig. 4 no provision is made for combining the two fluids in the heater C and heating the mixture before discharge although this method of operation is contemplated. The significance of Fig. 4 is to show that the method is not limited to the use of vertical heaters as shown in Fig. 1 but may as well be used in a horizontal type heater more conventional to the art.

By the method of heating two separate fluids, as described in the four figures, fluids of different types can be preheated in separate units or tube banks to a desired degree and thereafter simultaneously heated in a third heater where the fluids are superheated to the extent necessary and thereafter combined prior to discharge from the third heater or upon discharge from the third heater. By an arrangement of this kind the temperature of the individual fluids at the point of mixing can be accurately controlled and this is done by controlling the outlet temperatures of the fluids as they are discharged from the initial zones of heating or preheating stages. To be more explicit, and as an example of the control obtained over the exit temperatures from heater C, fluids of different character may be initially heated in heaters A and B to 950° F.

In heater C the fluid streams A and B are subjected to additional heating sufficient to raise steam A to a discharge temperature of 1350° F. and stream B to a discharge temperature of 1500° F. By controlling the exit temperatures of the streams as they are discharged from heaters A and B, an accurate control may be maintained upon the respective discharge temperatures of the two streams from heater C.

The above control enables me to obtain a wide range of flexibility in the amounts of the respective fluids and the temperatures to which the respective fluids are heated, important in obtaining optimum operating conditions.

It will be understood that certain features and

sub-combinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, I claim:

1. In the conversion of light hydrocarbons, the steps of heating a light oil in a first zone to a predetermined outlet temperature, heating separately in a second zone a normally gaseous fluid to a temperature different from that to which the fluid is heated in said first zone, then passing streams from said first and second zones separately into a third zone where the temperatures of the two streams are increased by a common heat source, combining said streams in the third zone and regulating the discharge temperature from said third zone by independently controlling the temperatures of the fluids passing from said first and second zones into said third zone.
2. In the conversion of unlike hydrocarbon fluids, the steps of heating one of the fluids in a first zone to a predetermined outlet temperature, heating separately in a second zone the other fluid to a temperature different from that to which the fluid is heated in said first zone, then passing streams from said first and second zones separately into a third zone where the temperatures of the two streams are increased by a common heat source, combining said streams in the third zone and regulating the discharge temperature from said third zone by independently controlling the temperatures of the fluids passing from said first and second zones into said third zone.

Certificate of Correction

Patent No. 2,457,096.

December 21, 1948.

HARRY R. SWANSON

It is hereby certified that errors appear in the printed specification of the above numbered patent requiring correction as follows:

Column 3, line 35, for the word "neat" read *heat*; column 5, line 45, for "steam" read *stream*;

and that the said Letters Patent should be read with these corrections therein that the same may conform to the record of the case in the Patent Office.

Signed and sealed this 3rd day of May, A. D. 1949.
